REGENERATIVE HEAT EXCHANGER

Uno Olof Blomquist, Västerås, Sweden

Application August 9, 1950, Serial No. 178,411

7 Claims. (Cl. 257—6)

1

This invention relates to rotary regenerative air preheaters in which a rotor enclosed in a shell is provided with heat accumulating elements through which flue gases and air pass in an alternating manner. In air preheaters of this type, there prevails a considerable pressure difference between the air duct and the gas duct. In order to reduce this pressure difference, sealing members have to be provided between the rotor and the stationary parts of the preheater. Said sealing members usually comprise strips arranged radially at the end faces of the rotor and adapted to slide on sector plates which separate the air side from the gas side, the sealing members further comprising strips arranged circumferentially on the rotor and strips disposed axially between the rotor and the shell. In spite of various improvements, particularly of the axially located sealing strips, for instance by making them externally adjustable, it was not possible to reduce the losses due to leakage to reasonable values. The major part of these losses is a result of air leaking through the space between the rotor and the shell from the air side to the gas side of the preheater. On account of the leakage losses, the power required for the flue gas fan is considerably increased, and cleaning of the flue gases in gas filters and ash separators is rendered more difficult.

The invention has for its object to provide means for eliminating, entirely or in part, leakage from the air side to the gas side. The invention is characterized by a draught fan connected to the space between the rotor and the shell on the air side of the preheater at a location upstream from the air discharge port of the shell for reducing the pressure prevailing in said space. The draught fan is preferably devised to reduce the pressure in said space down to the pressure which prevails on the gas side in the space between the rotor and the shell. Due to this arrangement, leakage through said space is entirely eliminated. Since the air quantity which would leak through said space constitutes the major portion of air leaking between the air side and the gas side, the efficiency of the preheater is considerably increased due to the arrangement according to the invention. The discharge conduit of the fan is preferably connected to the air duct in front of or after the preheater. In the last named alternative, the discharge conduit of the fan may have inserted therein a heat exchanger located in the gas duct. By means of this heat exchanger, the quantity of air passing through

the fan can be preheated substantially to the same temperature as the main air stream.

The invention will now be described more clearly with reference to the two embodiments thereof illustrated in the annexed drawing. Fig. 1 shows in diagrammatic manner an elevation, partly in section, of a preheater embodying this invention. Fig. 2 illustrates the cooperation between a sector plate and radial sealing strips; and Figure 3 is similar to Figure 1 but shows a slightly modified embodiment of the invention.

The air preheater illustrated comprises a rotor 2 adapted to rotate about a vertical axis 1, said rotor having a great number of comparatively thin-walled plates which may be corrugated as indicated in Fig. 2. The air duct is indicated at 3 and the direction of flow of air through said duct is indicated by the arrows 4. The flue gases pass through the gas duct 5 in an opposite direction, as indicated by the arrows 6. The air duct and the gas duct are separated from each other by means of sector-shaped plates 7 and 8, on a housing enclosing the rotor, and in contact with radially extending sealing strips 9 and 10, respectively, secured to the rotor. It is to be understood, of course, that the housing has axially aligned air inlet and outlet ports with which the inlet and outlet portions of the air duct 3 communicate; and gas inlet and outlet ports likewise communicating with the gas inlet and outlet portions of the gas duct 5. The rotor further has circumferentially extending sealing strips 11 and axially extending sealing strips, not shown, between the periphery of the rotor and a shell 12 which surrounds the rotor and constitutes part of the rotor housing. That portion of the rotor which during the rotation of the rotor is passed by fluid gases, accumulates heat from the gases and upon continued rotation transfers heat to the air passing in a counterflow direction through the air duct. As will appear from Fig. 2, the sector plate 7 extends substantially diametrically over the end face of the rotor. The angular distance between consecutive sealing strips 9 is somewhat smaller than the sector angle of the plate 7. Consequently, at any time, at least one sealing strip 9 will slide on the plate 7 on either sides of the axis of rotation so as to act as a sealing member between the air side and the gas side of the preheater. Before a sealing strip comes out of engagement with the plate 7, the next following sealing strip has already engaged the plate. Between the two sealing strips, the plate 7 and the end face of the rotor, there is temporarily formed a closed space, and the air quantity enclosed in said space is con-

vveyed to the gas side. Similar conditions prevail at the lower face of the rotor where closed spaces are formed between the plate 8 and the sealing strips 10.

In the operation of the air preheater, the pressure prevailing in the inlet part of the air duct may amount to, for instance, +3 inches of water, in the outlet portion of the air duct after the preheater to +1", in the gas duct before the preheater to -1.5", after the preheater to -4", in the space 13 between the rotor and the shell on the air side to -3/4" and in the corresponding space 14 on the gas side to -1.5". On account of the pressure difference between the spaces 13 and 14, which difference according to the example amounts to .75" of water, part of the air will flow over to the gas side along the periphery of the rotor. The leakage losses resulting therefrom can be entirely eliminated by reducing the pressure prevailing in the space 13 substantially to the pressure prevailing in the space 14 so as to stop the flow from the air side to the gas side.

To this end, the space 13 is by means of a conduit 15 connected to a draught fan 16 which maintains the pressure in the space 13 at substantially the same value as the pressure prevailing in the space 14 on the gas side. As indicated in Figure 3, the air quantity withdrawn from the space 13 may be returned to the inlet portion of the air duct 3 by a conduit 17. However, it is deemed more suitable to discharge said air quantity to the outlet portion of the air duct, as indicated in Figure 1. In order to avoid a decrease in temperature of the main air stream by the air quantity withdrawn by the fan, said air quantity may be supplied, through a conduit 19, to a heat exchanger 20 provided in the gas duct 5. In this heat exchanger, the air quantity withdrawn by the fan can be heated to substantially the same temperature as the main air stream and is then united with the main air stream by means of a conduit 21 opening into the air discharge portion of the air duct.

As a result of the arrangements described, the volume flowing through the gas duct after the preheater is reduced by the quantity of air which otherwise would leak from the space 13 to the space 14. The practical importance of this advantage will be evident from the fact that said air quantity may amount up to 15% of the total air quantity. Consequently, the power required for the flue gas fan will be materially reduced, and the devices for cleaning the flue gases can be made in a more simple manner. The power required for the fan 16 is compensated for by a corresponding reduction of the power required for the fan for the main air stream.

It may be suitable to provide additional sealing means between the rotor and the shell 12 along a plane at right angles to the plane of Fig. 1 and through the axis of rotation 1. For instance, such sealing means may consist of two sealing strips located on opposite sides of the axis of rotation for separating the air side from the gas side and reducing the power required for the fan 16.

As indicated by conduits 22 and 23 of Figure 1, the suction conduit 15 of the fan may also be connected to the spaces between the sector plates 7, 8 and the cooperating sealing strips 9, 10 so as entirely or in part to eliminate the quantity conveyed through said spaces from the air side to the gas side.

What I claim is:

1. An air preheater of the regenerative type comprising a rotor with a number of axial passages therethrough provided with heat accumulating elements and rotatable in a housing the interior of which has an air side and a hot gas side, said housing having axially aligned air inlet and outlet ports at its air side and axially aligned hot gas inlet and outlet ports at its hot gas side, and said rotor being rotatable about an axis intermediate and parallel to those of the air and hot gas ports of the housing to carry said elements successively through the hot gas and the air sides of the housing, said rotor having a side wall cooperating with the adjacent wall of the housing to define a circumferential space around the rotor, said rotor at the ends of its passages, being imperfectly sealed from said space so that air and hot gas from the rotor passages may enter said circumferential space at the air side and the hot gas side of the housing, respectively, at a pressure differential which promotes their intermingling, said preheater being characterized by: a suction fan communicated with said space at the air side of the housing for withdrawing air from the space at the air side of the housing at a rate such as to maintain the pressure of the air therein substantially equal to the pressure of the hot gases in the space at the hot gas side of the housing, irrespective of the hot gas and air pressures which obtain in the rotor passages.

2. In an air preheater of the regenerative type comprising a rotor with a number of axial passages therethrough provided with heat accumulating elements, and a housing in which the rotor is rotatable and the interior of which has an air side at one side of the rotor axis, with air inlet and outlet ports aligned on an axis parallel to that of the rotor, and a hot gas side at the opposite side of the rotor axis with hot gas inlet and outlet ports aligned on an axis parallel to that of the rotor, said rotor also having a circumferential wall cooperating with the housing to define a circumferential space around the rotor which space, at the hot gas and air sides of the housing, receives hot gas and air, respectively, from the rotor passages due to imperfect seals at the ends of the rotor passages, means for precluding intermingling of such hot gas and air in said space which results from the air therein having a greater pressure than that of the hot gas, said means comprising: a suction conduit connected to the housing in communication with the air side of said space; and a suction fan in said conduit for withdrawing air from said space at a rate such as to maintain the pressure of the air therein substantially equal to the pressure of the hot gases in the hot gas side of said space, irrespective of the hot gas and air pressures which obtain in the rotor passages.

3. The air preheater of claim 2, further characterized by an air outlet duct communicated with said air outlet port; and further characterized by duct means communicating said conduit with said air outlet duct for passing the air withdrawn from said space into said air outlet duct.

4. The air preheater of claim 3, further characterized by a heat exchanger in said duct means for heating the air withdrawn from said space before the same is fed into said outlet duct.

5. The air preheater of claim 4, further characterized by a hot gas outlet duct communicated with said hot gas outlet port; and further char-

acterized by the fact that said heat exchanger is located in said hot gas outlet duct, so that air withdrawn from said space is passed in heat exchange relationship with hot gas which has emerged from the air preheater, and is thereby preheated before being fed to said air outlet duct.

6. The air preheater of claim 2, further characterized by an air inlet duct communicated with said air inlet port; and further characterized by duct means communicating said conduit with said air inlet duct for conducting air withdrawn from said space back into said air inlet duct.

7. In a rotary air preheater of the regenerative type comprising a rotor with a number of axial passages therethrough provided with heat accumulating elements, and a housing in which the rotor is rotatable and the interior of which has an air side at one side of the rotor axis, with air inlet and outlet ports aligned on an axis parallel to that of the rotor, and a hot gas side at the opposite side of the rotor axis with hot gas inlet and outlet ports aligned on an axis parallel to that of the rotor, said rotor also having a circumferential wall cooperating with the housing to define a circumferential space around the rotor, and said housing having sector-like end plates extending substantially diametrically across the end faces of the rotor, defining an intermediate zone in the housing and cooperable with radially extending sealing members on the end faces of the rotor to temporarily form closed compartments in the rotor as each rotor passage is carried through said intermediate zone during rotor rotation and in which compartments air is carried from the air side of the housing to the hot gas side thereof; means for

5 precluding intermingling of hot gas and air which respectively occupy the hot gas and air sides of said circumferential space around the rotor and which are received into said space from the rotor passages due to imperfect seals at the ends of the rotor, said means comprising a suction conduit connected with the housing and communicated with the air side of said space, and a suction fan in said conduit for withdrawing air from the air side of said space at a rate such as to maintain the pressure of the air therein substantially equal to the pressure of the hot gases in the hot gas side of said space; and means for substantially preventing air in said compartments carried from the hot gas side of the housing through the intermediate zone from being transferred to the hot gas outlet port of said housing, said means comprising a second suction conduit connected with one of said 10 sector-like end plates and communicated with said intermediate zone in the housing and with said first named suction conduit, at the suction side of said fan, for withdrawing air from each of said closed compartments as the compartment moves through said intermediate zone during rotor rotation.
